UNITED STATES PATENT OFFICE

2,616,444

POULTRY DRINKING FOUNTAIN

Clarence Norland, Cypress, Calif.

Application February 23, 1950, Serial No. 145,790

1 Claim. (Cl. 137—408)

1

My invention relates to drinking fountains particularly designed for poultry use and the principal objects of my invention are, to generally improve upon and simplify the construction of the existing forms of poultry fountains, particularly those wherein the refilling action is automatic, to provide the fountain with a readily adjustable valve for controlling the flow of water into the cup or bowl and, further, to provide simple means for mounting the cup or bowl so that same may be readily manipulated without disassembly while being cleaned.

With the foregoing and other objects in view, my invention consists in certain novel features of construction and arrangement of parts, herein more fully described, claimed and illustrated in the accompanying drawing, in which:

Fig. 1 is a front elevational view of a poultry drinking fountain constructed in accordance with my invention.

Fig. 2 is a vertical section taken on the line 2—2 of Fig. 1.

Fig. 3 is a horizontal section taken on the line 3—3 of Fig. 2.

Fig. 4 is a perspective view of the adjustable valve used in my improved fountain.

Referring by numerals to the accompanying drawing which illustrates a preferred embodiment of my invention, 10 designates a water supply duct, to which is detachably secured a valve body 11, having a duct 12, and formed in the intermediate portion of said duct is an annular valve seat 13.

A housing composed of side walls 14, bottom plate 15 and rear wall 16 partially encloses the lower portion of valve body 11 and is pivotally connected to the lower front portion of said body, by the lower leg 17, of a substantially hairpin-shaped wire member which includes an upper leg 18 and a coil 19 connecting said legs at one end.

Lower leg 17 of this wire member passes through the the lower front corner of body 11 and through the adjacent portions of side walls 14.

Under normal conditions leg 18 occupies notches 20 in the upper front edges of side walls 14, thus providing a stop to limit the upward-swinging movement of the water bowl connected to walls 14 and bottom plate 15, and when said leg 18 is swung downward and engaged in notches 21 formed in the lower front edges of side walls 14, the water cup or bowl may be swung upward into a substantially vertical position to facilitate emptying and cleaning.

2

Connected to the front edges of side walls 14 and front edge of bottom plate 15 is the rear portion of the water containing cup or bowl 22 and in order to permit limited downward swinging movement of this water cup, the face of valve body 11 immediately in front of rear wall 16 is cut away to provide a clearance notch 23. Depending from the rear portion of bottom plate 15 is a short arm 24, to which is adjustably connected by a clamping screw 25, a weight 25a for counterbalancing cup 22 and its contents.

Seated in bottom plate 15 is a screw 26, in the upper end of which is seated a plug 27, of rubber or the like, and which functions as a valve to engage on seat 13 and thereby control the flow of water through duct 12 into cup 22.

Under normal conditions, or with cup 22 filled with water, valve 27 is held against its seat, thus cutting off the flow of water to the cup and as the water is withdrawn from said cup by the drinking poultry, counterbalancing weight 22 will act to swing cup upward on its axis, leg 17, thus withdrawing valve 27 from its seat to permit water to flow through duct 12 into the cup and thereby refill same.

The weight of the water thus admitted to cup 22 acts to swing same downward to its normal position and restore valve 27 to its seat, thus automatically cutting off further flow of water through the valve.

Obviously, my improved fountain, with minor structural changes, may have the valve body horizontally disposed, for connection to a horizontal water supply pipe.

Thus it will be seen that I have provided a poultry drinking fountain which is simple in structure, capable of being easily and quickly adjusted, wholly automatic in operation, easily cleaned and very effective in performing the functions for which it is intended.

Minor changes in the size, form, and construction of the various parts of my improved poultry drinking fountain may be made and substituted for those herein shown without departing from the spirit of my invention, the scope of which is set forth in the appended claim.

I claim as my invention:

In a poultry drinking fountain, a valve body provided with a duct and a valve seat formed therein, a housing partially enclosing the discharge end of said valve body, a water cup carried by said housing, a member having a part for pivotally connecting said housing to said valve body, said member also having a part for limiting the swinging movement of said housing

and cup, an adjustable valve carried by said housing for engaging the seat in said duct and an adjustable counterweight carried by said housing.

CLARENCE NORLAND. 5
